UNITED STATES PATENT OFFICE

HERMAN C. C. ENGBERG, OF KEARNEY, NEBRASKA

ILLUMINATED SIGN

Application filed October 6, 1930. Serial No. 486,759.

This invention relates generally to illuminated signs and more particularly to a sign of this character which is in the nature of a register for use in hospitals but it is understood, of course, that a sign in accordance with this invention may be used for any purpose or in any place for which the same is found adapted and desirable.

An important object of the invention is to provide in a manner as hereinafter set forth, an illuminated sign of the aforementioned character embodying means for enabling it to be expeditiously determined when a doctor or other person is present in the hospital or other building.

Another important object of the invention is to provide an illuminated sign of the character set forth embodying a housing or casing having an open front in which are mounted a plurality of translucent removable panels upon each of which the names of the doctors or other persons are placed, the invention further including manually operable means associated with each of the panels for shielding said panels from the light within the housing or casing, thus rendering the names on the panels invisible from the front of the sign.

Another important object of the invention is to provide an illuminating sign embodying a novel construction and arrangement of parts whereby the panels may be expeditiously removed or replaced when it is so desired, to permit the names thereon to be changed.

A still further important object of the invention is to provide resilient means for yieldingly retaining the light intercepting shutters in operative or inoperative position after said shutters have been manually shifted.

Other objects of the invention are to provide an illuminated sign of the character set forth which will be attractive in appearance, simple in construction, strong, durable, efficient in use and which may be manufactured at low cost.

All of the foregoing and still further objects and advantages of the invention may become apparent from a study of the follow-

ing specification, taken in connection with the accompanying drawings wherein like characters of reference designate corresponding parts throughout the several views, and wherein:

Figure 1 is a view in front elevation of the sign constructed in accordance with this invention.

Figure 2 is a view in side elevation thereof.

Figure 3 is a vertical longitudinal sectional view of the sign.

Figure 4 is a horizontal sectional view taken substantially on the line 4-4 of Figure 3 looking in the direction indicated by the arrows.

Figure 5 is a view in top plan showing the panel supporting units separated.

Figure 6 is a fragmentary view in front elevation showing the panel supporting units separated.

Figure 7 is a view in elevation looking at the rear of the panel supporting units showing the same in position in the front wall of the housing with the light intercepting shutters in operative position.

Figure 8 is a fragmentary view broken away in vertical cross section and showing a resilient means for retaining the shutters in operative or inoperative position.

Figure 9 is a fragmentary enlarged view in vertical section showing the means for removably mounting the translucent panels in position in the units.

Figure 10 is a detail view in perspective of one of the shutters.

Figure 11 is a transverse sectional view through one of the panel frames with the parts therein.

Referring to the drawings in detail, it will be seen that the reference numeral 1 designates generally a housing or casing which is open at its front. An incandescent light bulb 2 is mounted at a suitable point on the rear wall of the housing or casing 1 and is electrically connected by conductor wires 3 with a suitable receptacle 4 in the lower wall of the housing or casing. A suitable switch 5 is mounted in the housing or casing 1 and interposed in the circuit to the bulb 2, the operating lever of the switch 5 being operable

through a slot 6 in one of the side walls of the housing or casing, as best seen in Figure 2 of the drawings. It is understood, of course, that any desired number of light bulbs may be mounted in the housing and that the receptacle 4 and the switch 5 may be located at any desired point. The interior of the housing or casing 1 is preferably suitably coated to reflect the light from the bulb 2 toward the open front of said housing or casing.

As best seen in Figure 3 of the drawings, the upper wall of the housing or casing 1 has its forward edge disposed rearwardly of the forward edges of the side and lower walls of the housing and said upper wall terminates in an upturned flange 7. The side walls and the lower wall of the housing or casing 1 terminate at their forward edges in the in-turned flanges 8.

20 A rectangular frame 9 of angle iron cross section is mounted telescopically and removably on the front portion of the housing 1. An integral panelled extension 10 is provided on the upper side of the frame 9 for the reception of the flange 7 for detachably securing the upper end of the said frame 9 to the housing or casing 1. A metallic strip 11 is secured beneath the upper side of the frame 9 for abutting engagement with the forward edge of the upper wall of the housing or casing 1 in the manner illustrated to advantage in Figure 3 of the drawings. Suitable means such as aligned eyes 12 may be provided on the lower end of the frame 9 and an adjacent portion of the lower wall of the housing or casing 1 for securing said lower end of the frame in position on the housing. A locking pin 13 is inserted through the eyes 12 to secure the lower end 40 of the frame to the housing.

An angular supporting bar 14 is fixed within the frame 9 adjacent the lower end thereof and projects into the housing or casing 1 when the frame 9 is in position on said housing or casing. Metallic strips 15 (see Figure 4) are mounted on the opposite sides of the frame 9 on the interior of said frame and project into the housing or casing 1 when the frame 9 is in position thereon. As clearly seen in Figure 4 of the drawings, the strips 15 are spaced from the adjacent edges of the vertical sides of the frame 9 and the angular bar 14 is spaced below the adjacent horizontal edge of the lower side of the frame 9. The marginal portions of the frame 9 which project inwardly beyond the strips 15 and the angular bar 14 are turned back in a manner to provide a double thickness of metal at these points and to provide a smooth edge. In fact, all of the marginal edges of the frame 9 are rolled or turned back to provide a smooth edge.

A pair of vertically disposed sign panel supporting frames 16 and 17 are removably mounted in the frame 9, the lower ends of

said sign panel supporting frames resting on the angular bar 14 in the manner best illustrated in Figure 3 of the drawings. Each of the frames 16 and 17 is provided with the superposed windows 18. Behind each of which windows a translucent sign panel 19 is slidably mounted in the pairs of opposed channel members 20 which are provided for this purpose. The frames 16 and 17 are identical in construction and each has one vertical marginal portion enlarged as at 21 and channelled as at 22 as will be seen each of the panel frames 16 and 17 is composed of a base plate 18' which contains the window 18 and to which the channel members 20 are connected. The ends of the base plate are bent over to form top and bottom parts of a panel frame and a strip 18'', of substantially G-shape in cross section is fastened to the channel members at the side of the panel frame opposite the enlargement 21. A channel shaped member 22' is connected to the opposite side of each panel frame to form the enlargement 21 on the channel 22 and the space for the spring 30. A strut 22'' is formed with or connected to those ends of the channel members 20 adjacent the enlargement 22 and is located in rear of the transparent members 19. The rods 27 are journaled in the strip 18'' and the member 22. The channel in the frame 16 is for the reception of the adjacent marginal portion of the frame 17 as best seen in Figures 4 and 5 of the drawings. When in position in the frame 9 the panel supporting frames 16 and 17 fit snugly between the metallic strips 15 of the frame 9. It may be well to here state that the housing or casing 1 and the frame 9 may be of any desired dimensions and any desired number of the panel supporting frames may be mounted in side by side relation, as will be apparent.

Referring now to Figure 7 of the drawings, it will be seen that an angular retaining bar 23 is hinged as at 24 for swinging movement on the interior of the frame 9 in the upper portion thereof and is adapted for engagement over the upper ends of the panel supporting frames 16 and 17 in a manner to retain the upper ends of said frames 16 and 17 in position in the frame 9. The retaining bar 23 has formed thereon an eye 25 which is adapted to be brought into alignment with an eye 26 on the upper end portion of the frame 16 and on the inner side of said frame 16. A pin is inserted in the aligned eyes 25 and 26 for securing the retaining bar 23 in operative position.

Rods 27 are mounted for rotary movement and also for slight horizontal sliding movement on the rear side of each of the frames 16 and 17 adjacent the lower edge of each of the translucent sign panels 19 and fixed on each of the rods 27 for swinging 125

movement therewith is a metallic shutter 27' adapted for swinging movement to a position adjacent the respective sign panels in a manner to shield said panels from the light bulb 2 in the housing or casing 1. The shutters 27' are adapted to be swung from the position indicated in full lines in Figure 9 of the drawings to the position indicated in broken lines in said Figure 9. As will be apparent, the translucent panels 19 are exposed to the light bulb 2 when the shutters are in the broken line position. Each of the rods 27 terminates at one end, in a right angularly disposed portion 28 which projects forwardly and is operable through the arcuate slots 29' provided for this purpose in the enlarged portions 21 of each of the frames 16 and 17. The portions 28 constitute operating levers or handles for the rods 27 and each has formed on its free end the knob or ball 29 to facilitate gripping the same. As will be readily apparent, the desired indicia is placed on the translucent panels 19. An elongated spring 30 is mounted in the enlarged portion 21 of each of the frames 16 and 17 inwardly of the inner wall of channel 22 and said spring 30 is supported against lateral movement in one direction by the vertically spaced lugs or abutments 31. The spring 30 in each of the frames 16 and 17 is operatively engaged with the lever portions 28 of the rods 27 in a manner to yieldingly urge the lever portions 28 and the rods 27 in one direction. It will thus be seen that the lever portions 28 and the rods 27 will be yieldingly retained in the end portions of the slots 29' into which said lever portions 28 are manually shifted by a person moving the shutters 27' to operative or inoperative position with respect to the translucent sign panels 19.

The comparatively short upper wall of the housing or casing 1 permits the frame 9 to be removed with the panels supporting frames 16 and 17 mounted in position by simply removing the locking pin 13 swinging the lower end of the frame outwardly from the housing or casing 1 and then elevating the frame 9 with respect to the housing or casing 1 in a manner to disengage the panelled extension 10 from the upturned flange 7. The frames 16 and 17 may then be removed from the frame 9 by withdrawing the locking pin from the aligned eyes 25 and 26 and swinging the retaining bar 23 upwardly away from the frames 16 and 17. Said frames 16 and 17 may then be swung outwardly and lifted out of the angular bar 14. The translucent sign panels 19 may then be removed as desired for changing names.

When the sign is assembled in position and in use, the light bulb 2 is illuminated by closing the switch 5, as will be apparent. Then, when a doctor or other person is in the hospital or other building and wishes his pres-

ence to be indicated, he operates the lever 28 which is adjacent the sign panel 19 bearing his name and swings the shutter 27' to the position indicated in broken line in Figure 9 of the drawings. As before explained, this operation exposes the translucent sign panels 19 to the light bulb 2 and the name thereon is thus rendered visible from the front of the sign. A conventional plug 33 is detachably connected with the receptacle 4 in the housing or casing 1 for supplying electric current from any suitable source to the light bulb 2. It is believed that the many advantages of a sign constructed in accordance with this invention will be readily understood, and although the preferred embodiment of the invention is as illustrated and described, it is to be understood that changes in the details of construction may be had which will fall within the scope of the invention as claimed.

What is claimed is:—

1. An illuminated sign of the character described comprising a housing having an open front, a lamp mounted in the housing, a plurality of sign supporting frames removably mounted in the open front of the housing, a plurality of translucent sign panels mounted in each of the frames, shutters mounted for swinging movement on the frames adjacent each of the sign panels and adapted for disposition in opposed relation to the panels in a manner to selectively shield the same from the lamp, means for manually operating the shutters.

2. An illuminated sign of the character described comprising a housing having an open front, a lamp mounted in the housing, a frame removably mounted on the front of the housing, a plurality of sign supporting frames removably mounted in the first named frame, translucent sign panels mounted in each of the sign supporting frames, a plurality of shutters mounted for swinging movement on the second named frames, adjacent each of the sign panels and adapted for disposition in opposed relation to the panels in a manner to selectively shield said panels from the lamp, means for manually shifting the shutters to operative and inoperative position with respect to the sign panels.

3. An illuminated sign of the character described comprising a housing having an open front, a lamp mounted in the housing, a frame removably mounted on the front of the housing, a plurality of sign supporting frames removably mounted in the first named frame, translucent sign panels mounted in each of the sign supporting frames, a plurality of shutters mounted for swinging movement on the second named frames, adjacent each of the sign panels and adapted for disposition in opposed relation to the panels in a manner to selectively shield said panels from the lamp, means for manually shifting the shutters to operative and inop-

erative position with respect to the sign panels, and resilient means common to all of the shutters of each of second named frames for yieldingly retaining said shutters in operative and inoperative position.

5 4. An illuminated sign of the character described comprising an open front housing including top, bottom and side walls, and a rear wall, the top wall terminating rearwardly of the side and bottom walls, an upturned flange on the forward marginal edge of the top wall, inturned flanges on the forward edges of the side and the bottom walls, a substantially rectangular frame removably mounted on the forward portion of the housing, a channeled extension on the upper end of the frame for the reception of the flange on the upper wall of the housing, means for securing the lower end of the frame to the 10 lower wall of the housing, a bar of angle iron cross section mounted horizontally in the lower portion of the frame and extending into the housing when the frame is in position on said housing, metallic strips mounted 15 vertically in the frame adjacent the opposite sides thereof and adapted to extend into the housing, a plurality of sign panel supporting frames removably disposed in the first named frame and engaged for rest on the bar 20 in said first named frame, the second named frames disposed between the metallic strips in the first named frame, an angular retaining bar hingedly mounted in the first named frame for engagement with the upper ends 25 of the second named frames, means for releasably securing the retaining bar to the second named frames, a plurality of translucent sign panels mounted in each of the second named frames, and means for selectively 30 shielding said panels from the lamp.

49 5. An illuminated sign of the character described comprising a housing having an open front, a lamp mounted in the housing, a frame disposed in the open front of the housing, 55 a plurality of translucent sign panels mounted on the frame, a plurality of rods rotatably and slidably mounted on the frame adjacent each of the sign panels, said frame being provided with a series of arcuate slots in its outer side adjacent each of the rods, an angular extension on one end of each of the rods, operable in the arcuate slots and constituting operating levers for actuating the rods, a shutter fixed on each of the rods for disposition 60 in opposed relation to the adjacent sign panels in a manner to shield said panels from the lamp, and resilient means mounted in the frame and operatively engaged with each of the extensions on the rods for yieldingly retaining said extensions in shifted position in the end portions of the respective slots.

65 6. An illuminated sign of the class described comprising a housing, having a plurality of windows in one face thereof, a transparent sign panel in each window, shutters

mounted for swinging movement on the inner wall of said face of the housing for covering the panel, manually operated means for swinging each shutter inwardly away from the panel to expose the same and a lamp in 70 the housing for illuminating the panel when the shutters are swung inwardly.

In testimony whereof I affix my signature.
HERMAN C. C. ENGBERG.
